Patented Dec. 20, 1921.

Vernie H. Mohler Inventor

By Richard B. Oliver, Attorney

UNITED STATES PATENT OFFICE.

VERNIE H. MOHLER, OF INDIANAPOLIS, INDIANA.

DESIGN FOR A DOLL'S HEAD.

60,050.

Specification for Design.

Patented Dec. 20, 1921.

Application filed September 26, 1921. Serial No. 503,400. Term of patent 7 years.

To all whom it may concern:

Be it known that I, VERNIE H. MOHLER, a citizen of the United States, residing at Indianapolis, in the county of Marion and State of Indiana, have invented a new, original, and ornamental Design for a Doll's Head, of which the following is a specification, reference being had to the accompanying drawing, forming a part thereof.

The figure is a perspective view of a doll's head showing my design.

I claim:—

The ornamental design for a doll's head, as shown.

VERNIE H. MOHLER.

Witnesses:

Mrs. PEARL M. POWERS,
SARAH WEST.
